[57] CLAIM

The ornamental design for a reconfigurable toy jet-
plane, substantially as shown and described.

DESCRIPTION

FIG. 1 is a front and side perspective view of a recon-
figurable toy jet-plane, showing my new design;
FIG. 2 is a front elevational view thereof;
FIG. 3 is a side elevational view thereof, the side oppo-
site being substantially a mirror image;
FIG. 4 is a rear elevational view thereof;
FIG. 5 is a top plan view thereof;
FIG. 6 is a bottom plan view thereof;
FIG. 7 is a front and side perspective view of the design
shown in FIGS. 1 through 6 reconfigured in a robotic-
humanoid configuration;
FIG. 8 is a front elevational view thereof;
FIG. 9 is a side elevational view thereof, the side oppo-
site being substantially a mirror image.
FIG. 10 is a rear elevational view thereof;
FIG. 11 is a top plan view thereof; and
FIG. 12 is a bottom plan view thereof.
